UNITED STATES PATENT OFFICE.

GEORGE GREGORY, OF LONDON, ENGLAND, ASSIGNOR OF TWO-THIRDS TO
ROBERT GREGORY, OF ISLINGTON, LONDON, ENGLAND, AND JOHN HENRY
FOSTER, OF GREENWICH, ENGLAND.

SMOKE-PREVENTING AND FUEL-SAVING DEVICE FOR BOILER OR OTHER FURNACES.

SPECIFICATION forming part of Letters Patent No. 694,147, dated February 25, 1902.

Application filed April 9, 1901. Serial No. 55,010. (No model.)

To all whom it may concern:

Be it known that I, GEORGE GREGORY, mechanical engineer, a subject of His Majesty King Edward VII of Great Britain, and a resident of 57 Victoria road, Kentish Town, London, N. W., England, have invented certain new and useful Smoke-Preventing and Fuel-Saving Devices for Boiler or other Furnaces, (for which I have made application for patent in Great Britain, No. 23,099, bearing date December 18, 1900,) of which the following is a specification.

My invention relates to a device or apparatus adapted for attachment to the furnace of any type of steam-boiler as a means for providing an induced current of air and steam, which is caused to impinge directly over and upon the fire, and by thereat mixing with the carbonaceous gases of the furnace a perfect combustion ensues and the issue of smoke from the uptake-shaft is entirely prevented—a desideratum on ocean-going vessels and in factories having a short uptake-shaft in crowded neighborhoods.

My invention consists of an inner casing or shield-plate fixed upon the inner surface of the furnace-front in such a manner as to form a chamber above and partly around the furnace-door opening, the said chamber being provided with suitable holes, apertures, or grids or gratings open to the atmosphere and through which air is admitted into the said chamber. A suitable inlet or retort pipe or pipes is or are fitted communicating with and leading from the said air-chamber into the furnace above and directed toward the fire, a small and cock-governed steam pipe or pipes communicating with the boiler above the water-level, being led therefrom to a specially-constructed nozzle in the center of the said inlet or retort pipe or pipes in the air-chamber and through which and the said inlet pipe or pipes steam is conveyed, which induces a strong current of air to be drawn through the said apertures in the furnace-front into the said air-chamber, which, mingling with the current of steam, causes a superheated current or water-gas to be driven almost noiselessly through the said inlet or retort pipe or pipes directly onto the furnace-

fire, which in practice has been found to bring about the perfect combustion of all the various gases generated in the furnace.

In order that my said invention and the manner in which I purpose employing the same in connection with any type of steam-boiler furnace may be fully understood, I have hereunto appended four sheets of drawings, in which I have chosen to show its application to three types of boilers, which will suffice to make clear the manner of using my invention in connection with other types of boilers. (Not shown.)

Figure 1 is an elevation of the front end of a two-furnace or Lancashire boiler to which my invention has been applied. Fig. 2 is a vertical longitudinal section of a boiler which must be regarded as taken through one of the furnaces of such a boiler, as Fig. 1, or through the furnace of a Cornish or like boiler. Fig. 3 is a much-enlarged sectional view of the improved nozzle (forming part of my invention) and the inlet or retort pipe of the air-chamber through which the compound current is directed onto the furnace-fire, Fig. 4 being an end view of the said nozzle with the steam-passage thereof in section.

My invention consists of casing or shield-plate A, fixed upon the inner face of the boiler-front B, thus forming an air-chamber, the shape and configuration of the said chamber being such as to partly surround the furnace-entrance above the ash-pit, and in the boiler-front B, I provide two or more holes or apertures C, (trumpet-mouthing or otherwise,) which form air-inlets to the chamber A, and in addition to such inlets or in lieu thereof (as occasion may require) I provide two or more other like air-inlets D in the bottom face of the said chamber at either side of the furnace-opening E, or in lieu of the apertures D, I may provide a grid or grids, grating or gratings in the bottom face of the said air-chamber at either or both sides of the furnace-opening, as indicated by F in Fig. 1.

From any part of the boiler above the water-level I provide a pipe or pipes G, each fitted at any desired part of its length with a cock or valve H for the purpose of regulating the force or current of steam, the said steam

- pipe or pipes G being led directly to one entrance or provided with any number of branch pipes J to lead to a like number of entrances into the chamber A or to the chamber A of 5 each furnace in cases where more than one furnace is provided—as, for instance, in the type of boiler illustrated by Fig. 1. At the point or points at which the said steam pipe or pipes join the air-chamber A a steam-nozzle K is provided, surrounded by a casing L of any desired formation, but for preference substantially that shown in Fig. 3 and facing the mouth of the said casing L, an opening 10 is formed in the shield-plate or back face of the chamber A, and inclosing the said opening is fixed upon the said shield-plate an inlet tube or retort M of any desired length and preferably slightly bent or curved in a downward direction, so as to direct the induced 15 current of air and steam upon the desired part of the furnace-fire.
- The manner of operation of my invention is as follows: The apertures C, D, or F, as the case may be, would freely admit air into the 20 chamber A, and the jet of steam issuing from the nozzle K and emitted from the mouth of the casing L would induce a current of air to be drawn from the chamber A in the direction of the arrows shown in the said chamber 25 30 in Fig. 3, and such air, mingling with the current of steam, would be forced through the inlet tube or retort M in the direction of the arrows therein shown, directly onto the furnace-fire, as shown in Fig. 2, and by reason of 35 the air in the chamber A becoming heated before mingling with the steam perfect combustion of the gases in the furnace would be effected and the object of my invention be thereby attained.
- 40 In cases where the marine or other boiler may have more than two furnaces the branch steam-pipes J may be provided with other

subbranch pipes leading to the several chambers A, and where desired the said branches J and the branches leading from J may each 45 be provided with a cock or valve H in addition to or in lieu of the one common cock or valve H in the steam-pipe G in order to regulate the force of the steam-current to each furnace, and in like manner each of the apertures C, D, or F, as the case may be, may be provided with means for closure in order to regulate the inlet of air to accommodate certain conditions of the boiler or the class of fuel being used. 50

55 It has been found in the experimental tests to which my invention has been subjected that the commonest and most smoky kind of fuel may be used, even pitch, tar, rubber, leather, and other refuse having been tried 60 without the slightest signs of emitted smoke, thus rendering my invention a great economizer of fuel as well as a smoke-consumer.

Having now particularly described and ascertained the nature of my said invention 65 and in what manner the same is to be performed, I declare that what I claim is—

In combination with a boiler-furnace, a casing or shield-plate A formed of one piece and secured to the inner face of the boiler-front 70 around the doorway, thus forming an air-chamber, a retort M secured to said casing and projecting over the bed of fuel, a nozzle K extending through the boiler-front, a case L secured to said nozzle and having an enlarged open rear end and a contracted front 75 portion in line with the retort M, and an air-inlet, substantially as described.

In witness whereof I have hereunto set my hand in presence of two witnesses.

GEORGE GREGORY.
